UNITED STATES PATENT OFFICE.

LOUISE A. MOCHEL, OF CHICAGO, ILLINOIS.

COPYHOLDER.

1,417,762.

Specification of Letters Patent. Patented May 30, 1922.

Application filed May 16, 1919. Serial No. 297,691.

To all whom it may concern:

Be it known that I, LOUISE A. MOCHEL, a citizen of the United States, residing at Chicago, in the county of Cook and State of Illinois, have invented new and useful Improvements in Copyholders, of which the following is a full, clear, and exact description.

My invention relates to copy holders and more particularly to the class used by typewriter operators, stenographers and clerks.

The object of my invention is to provide a copy holder, the rack of which can be adjusted vertically and horizontally to and

from its support to bring the copy in front of operator, and render it unnecessary to keep twisting his head or looking sidewise, particularly when its base is limited to a very small surface on which it can be sup-

ported. It is also the object of my invention to provide for the vertical extension of the plate upon which the copy is held, so that it can be used for holding legal cap and other comparatively long copy above the surface

upon which its support rests. Yet another object of my invention is to provide a novel means or marker for indicating the lines of the copy. This and other objects are accomplished by means hereinafter described

and as particularly pointed out in the claims.

In the drawings:

Figure 1 is a side view of my invention.

Figure 2 is a front view of the same.

Figure 3 is a horizontal section of the beam that supports the rack of the copy holder, taken on dotted line 3, 3, Figure 1.

Figure 4 is a vertical section of the copy holding plate or rack, taken on dotted line 4, 4, Figure 2.

Figure 5 is a transverse section of a fragment of said rack, taken on dotted line 5, 5, Figure 4.

Figure 6 is a perspective view of a fragment of said rack, illustrating a modification of the marker carrier.

My improvement comprises a base 7 of any suitable design, from the center of which a stud, 8, arises, that is preferably square in cross-section. A tubular upright 9, which is also square in cross-section, is fitted over stud 8, and one side of its lower end portion has a slot 10, through which a thumb-screw, 11, passes, that is tapped into stud 8 to securely fasten upright 9 thereto.

12 represents the horizontal beam which is secured to upright 9, so to be capable of ad-

justment either vertically or horizontally by a clip 13. This clip consists of a U-shaped strip of metal, the distance between the legs of which corresponds to the width of the upright, and said legs are of such length that, when the clip is properly placed upon the upright, their ends will extend beyond the same. The extensions of the legs of the clip are provided with rectangular openings, 65 14, 14, for the reception of the beam 12, which latter can be adjusted longitudinally in a horizontal direction or vertically at any height by tightening a thumb-screw, 15, tapped through the cross web connecting the 70 legs of the clip 13. I prefer to have the end of this thumb-screw bear against a shim, 16, and clamp the upright between the shim and beam 12. This method of securing the beam to the upright enables the operator to easily 75 adjust the beam to any position within its length or the height of the upright so as to bring the rack (which will be hereinafter described) in front of him over the typewriter and greatly facilitate his work and 80 enable him to keep his eyes on his work and reduces the possibility of mistakes.

I prefer to make said beam tubular and rectangular in cross-section. One end of the beam forms a socket for the tang 17 of 85 a pivotal head 18. The end of this head opposite said tang is bifurcated to permit the insertion of a lug 19 that is pivoted between the resultant bifurcations by a screw or other means 20. This lug projects from a 90 screw-plate 21 to which a rack 22 is attached.

Rack 22 consists of a rectangular plate of sheet metal and its lower edge is flanged outwards to form a ledge 23, upon which a 95 book or pamphlet may rest. The center of length of the outer edge of this ledge has an upwardly projecting extension which constitutes a guard 24 that assists in holding the book or pamphlet in place on the rack. 100

The rack 22 can be made vertically extensible by means of a vertically adjustable supplemental rack 25, which consists of a rectangular sheet of metal plate of the same width as the rack, but of less height, and it 105 is retained in place by means of the thumb-nuts 26, which engage permanent screws 27, the heads of which are secured in rack 22, and which project rearwardly through vertically elongated slots 28 in the supplemental 110 rack.

The right hand side of the supplemental

rack is provided with a clamp 29, which consists of a suitable shaped strip of flat spring steel, that has one end riveted or otherwise secured to the back of the supplemental rack 5 and then curves around the vertical edge of the rack and bends towards and presses against the front surface of the same. The object of this clamp is to bear against and hold the upper right hand portion of the 10 copy in place in a well known manner.

Supplemental rack 25 at or near its upper right hand corner is provided with a forwardly projecting lug 30, that has a suitable opening therein up through which a 15 vertically disposed guide-bar 31 extends. The lower end or heel of this guide-bar extends to and is secured in a suitable socket 32, which is made in one piece with a U-shaped bracket, 33, the legs of which latter 20 project forwards and provide bearings for a transverse rotatable shaft 34. The right hand end of this shaft extending beyond the right hand vertical edge of rack 22, is provided with a suitable wheel 35, which is 25 grasped when it is desired to rotate said shaft.

The guide-bar is separated from the front surface of the rack a suitable distance and is parallel thereto, and between its support 30 and 32 it has a tubular carrier 36, surrounding it, that is rectangular in cross-section. The bore of this carrier is of the same width as said bar 31, but is greater in depth and leaf springs 37, 37, extend from 35 the outer side of its ends that are bent toward and bear against the outer side of the guide-bar. The purpose of these springs is to create sufficient friction to retain said carrier in any position to which it may be 40 vertically adjusted on the guide-bar. On the left hand side of this carrier is a plate secured thereto which extends at right angles to the rack and which has its horizontal edges bent over to form a holder 38, for 45 the reception of the outwardly bent end 39 of a marker 40. This marker and its end consists of a flat strip of sheet steel and it extends horizontally from holder 38, across the front of the rack and at the point 50 where its end 39, is bent outwards its edges are recessed as shown at 41, so that when it is desired to remove the marker a clearance is provided for the folded over edges of the holder.

55 The lower end of carrier 36, is provided with a snap hook 42, into which the eye, 43, is attached to the upper end of a tape 44 is caught. The lower end of tape 44, is wound

around the shaft 34 between its bearings. Thus it will be noted that when the carrier 60 has been pushed up on guide-bar 31 as far as it will go, the wheel 35 can be grasped and turned to wind the tape on shaft 34 and draw the carrier 36 and the marker 40 towards the bottom of the rack as far as 65 desired, and that when said wheel 35, is released the springs 37, 37, will frictionally hold and retain the marker in any position to which it may be adjusted.

In Figure 6, I show a preferred construction of means for manipulating the marker. In this preferred construction, the right hand vertical edge of the rack 22, is bent over but separated from the face of the same to form a guide 46 for a carrier 47. This carrier 47, in cross-section describes a U-shaped figure, the rear leg 48 of which laps over and bears against the rear side of the rack 22 adjacent to its right hand vertical edge. The edge of its forward leg has an extension 49 that extends toward the outer face of the rack and then parallel thereto toward the back of the guide 46. A marker 50 consisting preferably of a flat strip made integral with the carrier extends 85 horizontally from the forward leg of its U-shaped part across the face of the rack and a tape 51 similar to tape 44 is secured to a hook which extends to and is wound upon the shaft 34 in the same manner as herein-before described.

The carrier is frictionally held in any position to which it may be adjusted on the right hand vertical edge of the rack by the pressure of the rear leg 48 of the 95 U-shaped portion of the carrier against the back of the rack.

What I claim as new is:

A copy holder comprising a rack having one of its vertical edges bent upon itself, 100 but spaced from the front face of the body portion of the rack to provide a guide channel, a carrier entering said channel and encompassing the bent edge portion to frictionally and adjustably engage the rear 105 face of said rack, a marker integral with said carrier and extending over the front face of said rack and means for vertically adjusting said carrier.

In witness whereof, I have hereunto set 110 my hand this 5th day of May, 1919.

LOUISE A. MOCHEL.

Witnesses:

EVA STREIT,

FRANK D. THOMASON.
